Primary Examiner — Cynthia R Underwood*(74) Attorney, Agent, or Firm* — Slayden Grubert Beard PLLC(57) CLAIM

The ornamental design for a reusable sealable snack bag, as shown and described.

DESCRIPTION

FIG. 1 illustrates a perspective top/front view of a reusable sealable snack bag, showing the new, original and ornamental design, wherein the snack bag is open and unsealed. FIG. 2 shows a front view of the reusable sealable snack bag shown in FIG. 1.

FIG. 3 shows a back view of the reusable sealable snack bag shown in FIGS. 2-3.

FIG. 4 shows a left side view of the reusable sealable snack bag shown in FIGS. 1-3.

FIG. 5 illustrates a right side view of the reusable sealable snack bag shown in FIGS. 1-4.

FIG. 6 shows a top view of the reusable sealable snack bag shown in FIGS. 1-5; and,

FIG. 7 shows a bottom view of the reusable sealable snack bag shown in FIGS. 1-6.
